UNITED STATES PATENT OFFICE.

ROGER M. WISE, OF OAKLAND, CALIFORNIA, ASSIGNOR, BY MESNE ASSIGNMENTS, TO
GRAY & DANIELSON MFG. CO., OF SAN FRANCISCO, CALIFORNIA, A COPARTNER-
SHIP CONSISTING OF THOMAS B. GRAY AND ERNEST G. DANIELSON.

RADIO TUNING DEVICE.

Application filed April 8, 1925. Serial No. 21,569.

This invention relates to a device for tuning radio frequency circuits, and more particularly to a device whereby a plurality of circuits can be tuned simultaneously.

It is now quite common, in connection with radio signaling, to use a plurality of circuits that are tuned to a frequency of a very high order. For example, in radio reception, there may be two or more stages of radio frequency amplification, in which the associated circuits are all to be tuned to a carrier wave. It has been proposed in the past to provide a common control for all such circuits, whereby a single manipulation only is needed for tuning all of the circuits. Such schemes have not met with material success, due to several factors now to be discussed.

In the first place, it is a very difficult matter to match a plurality of tuning devices, whether they be variable inductances or variable condensers, in such manner that when varied, they keep each of the associated circuits in substantially exact tune with all the other circuits. Furthermore, when manipulating devices operating in connection with radio frequency energy, it is found that the location of these devices relative to other objects has a very material effect upon the tuning; for example, stray capacitance and inductance between elements of the same or different circuits may easily cause these effects. The result is that even if exact equality be present in the tuning of a plurality of circuits, there is no certainty that the equality will be maintained as the tuning devices are moved in the process of tuning.

It is one of the objects of my invention to make it possible to adjust the tuning devices separately and independently, while in no wise interfering with their simultaneous operation when desired. In this way, it is possible to adjust the tuning of the circuits roughly by simultaneous tuning, and then to adjust the circuits independently by a fine adjustment.

The present invention is best exemplified in variable condensers, in which there are relatively movable plates; it is therefore another object of my invention to make it possible, in condensers that are mechanically connected for simultaneous operation, to

vary the relative positions of the plates of at least some of the condensers.

My invention possesses other advantageous features, some of which, with the foregoing, will be set forth at length in the following description, where I shall outline in full that form of the invention which I have selected for illustration in the drawings accompanying and forming part of the present specification. Although I have shown in the drawings but one embodiment of my invention, I do not desire to be limited thereto, since the invention as defined in the claims may be embodied in other forms also.

Referring to the drawings:

Figure 1 is a rear view of a portion of a panel on which a pair of condensers are mounted, and which embody my invention, some of the parts being broken away; and

Fig. 2 is a top plan view of the condensers and the panel illustrated in Fig. 1.

In the present instance I illustrate the invention as applied to condensers built in accordance with the disclosure in a prior application filed July 26, 1924, in my name entitled "Variable condenser" and having Serial Number 728,480. Furthermore, I illustrate a panel mounting 11, which is now quite common in radio receiving sets. One of the condenser structures 12 is mounted directly on this panel, and will now be described.

In the present instance the condenser structure 12 has a supporting disc 13 of insulation material, which is fastened upon the back of panel 11 by the aid of a plurality of screws 14. Projections such as 15 extend from the disc 13 and serve not only to accommodate the screws 14, but also to space the disc and the structure carried thereby from the panel 11. This structure includes the movable sets of condenser plates 16 and 17, which are arranged to overlap to any desired extent between limits. To support these sets of plates, a pair of stationary rods or studs 18 and 19 is provided, which studs are rigidly fastened at one end to disc 13, in the projections 20 on this disc. A series of brass spacers 21 is passed over each stud, and the plates 16 and 17 have ears 22 that are passed over the studs between the spacers. The ears are each soldered to the

spacers, which are so arranged that the plates 16 and 17 interleave.

The spacers 21 and plates 16 and 17 are mounted for rotation on studs 18 and 19, and for producing this rotation, gears 23 and 24 are fastened to the end spacers. These gears which intermesh, are preferably made from insulation material, and are journaled on studs 18 and 19. In order to hold the sets of plates 16 and 17 against axial removal, and for providing a stiffening member, a strip 25 of insulation is placed between the studs 18 and 19, and binding post structures 26 are used to hold the strip and the plate assemblies together. It is evident that rotation of one or the other of the pair of gears 23, 24 will produce relative movement of the sets of plates, whereby they may be interleaved to any desired extent.

In order to keep the plate structure rigid and to ensure that all of the plates of each set are in good electrical connection with each other, each of the plates is provided with an ear 27 at the top, and another ear 28 at the bottom; all of the ears 27 and 28 of all of the plates are bent so that each overlaps the adjacent ear of the next plate in the set, and are joined as by soldering. The result is that the ears of a series form practically a solid bar, such as 29, connecting all of the plates of a set. Furthermore, each binding post structure 26 includes a terminal 30 having ears by the aid of which connections can be made to a circuit, and to which pigtail connections such as 31 may lead from the associated plate assembly 16 or 17.

Sufficient friction is provided in the moving parts, as is customary, to ensure that the condenser plates can be retained in any relative position until it is desired to change the setting.

The operation of gears 23 and 24, and consequently of the plates 16 and 17 is effected in this instance by the aid of a small pinion 32 meshing with gear 23. This pinion has a shaft 33 extending through panel 11 as well as through disc 13. At the free extremity and on the front side of the panel 11, the shaft carries any well-known form of tuning dial 34, having a knob 35 for manual control. It is evident that manipulation of dial 34 by the aid of knob 35 causes a corresponding rotation of gears 23 and 24. The pinion 32 is held in place against removal by the aid of a forked member 36 of thin metal straddling the shaft 33 on the rear side of the disc 13. This member is held in place by a screw 37 engaging the disc 13, as well as by a projection 38 entering into an aperture 39 in this disc.

In order to limit the extent of movement of the plate structures 16 and 17, a pair of stops 40 and 41 is provided on the rear of gear 23, which stops are adapted to cooperate with a stationary stop 43 located on the disc

13. These stops limit the amount of rotation of gear 23.

The description of the condenser structure 12 is now complete. This description has been somewhat detailed, but only for the purpose of providing one example of the kind of apparatus with which my invention can be utilized. In the present instance, both sets 16 and 17 of condenser plates are movable; but it is evident that other well-known forms of condenser structure could be utilized, in which one set of plates is stationary.

With the type of condenser disclosed, however, it becomes a simple matter to provide another similar condenser structure such as 44 which can be adjusted by the aid of the same knob 35 simultaneously with the adjustment of condenser 12. All that it is necessary to do is to intermesh the adjacent gears 45 and 23 of the condenser structures. When this is done, it is evident that all of the gearing is rotated by rotation of pinion 32. Of course in the condenser structure 44, there is no equivalent to this pinion.

The arrangement as now described is such that both condensers 12 and 44 are adjusted in unison. In accordance with my invention, it is possible to impart a supplementary movement in either direction to the second condenser 44, whereby the slight irregularities of the two radio frequency circuits associated with the condensers, may be compensated for. This result, I have found, can be accomplished by taking into account the manner in which motion is imparted to gear 45. If we consider for the moment that gear 23 is held stationary, and that a planetary motion be imparted to gear 45, so that it rolls on the periphery of gear 23, it is evident that the gears 45 and 46 of condenser 44 will rotate about their own axes. This rotation will of course produce a relative movement of the plates of condenser 44. In this way, by proper extent of planetary motion, any desired supplementary adjustment in either direction, can be imparted to condenser 44.

In order to make this planetary movement possible, the condenser structure 44 is bodily mounted on a flat insulation support 47, by the aid of screws 48. This support is pivoted at one end on an axis coincident with that of gear 23, and on the back of panel 11. A screw or bolt 49 may serve conveniently as the pivot for the support 47.

For the purpose of moving the support 47 about its pivot, I make use, in the present instance, of a gear movement, including a pinion 50. This pinion is fastened to a shaft 51 extending through the main panel 11 and having a thumb button 52 by the aid of which it can be rotated. This pinion meshes with a segment 53 having its center at that of the support 47 and fastened to the outer

surface of the support by the aid of bolts 54. The segment 53 has a sufficiently large angular extent to ensure that under any usual circumstances, any desired supplementary setting can be secured for condenser 44. The support 47 has a pair of projections 55 which serve, in conjunction with pinion 50, to limit the movement of the support. It is also possible to ensure against accidental disturbance of the supplementary setting, by providing sufficient friction in the movable parts.

In the present instance a bank of only two condensers is disclosed. It is possible nevertheless to extend the idea to any number of condensers, by a continued succession of mountings, each pivoted on an axis of the gear of the previous condenser. Furthermore, if only three condensers are to be thus controlled, it is possible to mount a support such as 47 on an axis coincident with that of the other gear 24 of the condenser 12, whereby substantially a symmetrical arrangement of the three condenser structures would exist.

The description of the apparatus is now complete. There remains only a brief outline of the manner of use of the device. First of all, the knob 35 is carefully turned until that circuit which is associated with condenser 12 is in tune; then due to the mechanical construction, the circuit with which condenser 44 is associated, is also approximately in tune. To bring it exactly in tune, knob 52 is carefully adjusted. After this first adjustment, the process can be repeated to tune both circuits still more accurately.

I claim:

1. In a device of the class described, a plurality of electrical instruments each having a rotatable shaft, means for mounting said instruments in side by side relationship with said shafts substantially parallel, a gang control for said instruments, and means for causing relative displacement between certain of said shafts in a plane substantially normal to said shafts to cause relative angular movement between the shafts of at least two instruments.

2. In a device of the class described, a plurality of instruments each having movable elements, means including a common operating member for simultaneously moving said elements, and means for shifting the position of at least one of said instruments with respect to another one of the instruments to move one of said elements independently of the others.

3. In a device of the class described, a plurality of electrical instruments each having a rotatable shaft, a base upon which the instruments are mounted, a gear train for operatively connecting said shafts, a gang control shaft for actuating said gear train

to simultaneously rotate the shafts of said instruments, and means for independently adjusting one of said instrument shafts comprising means for shifting the pivotal axis of one of the gears of said train and simultaneously rotating the same relative to the base.

4. In combination, a pair of electrical tuning devices, each including a gear and a movable element connected to the gear whereby movement may be imparted to the element, the gears of the tuning devices intermeshing whereby simultaneous variation can be secured, and means for imparting to one of said gears a planetary movement with respect to the other, whereby the tuning device associated with the gear having a planetary movement may be adjusted independently.

5. In combination, a variable tuning device, including a pair of relatively movable elements and a gear for imparting this relative movement, a second tuning device similar to the first mentioned one, a pivotally mounted support for said second tuning device, the axis of the pivot being coincident with that of the gear on the first tuning device, and said second tuning device having a gear meshing with said first-mentioned gear and serving to impart relative motion of the movable elements of the second tuning device simultaneously with the adjustment of the first tuning device, and means for moving said pivotally mounted support about its axis, whereby a planetary motion is imparted to said second gear.

6. In combination, an electrical instrument having a movable element, and a gear mechanically connected to said movable element, a second electrical instrument also having a movable element and a gear mechanically connected thereto, said two gears intermeshing, and a pivotally mounted support for said second instrument, said support having a pivot with an axis coincident with that of the first gear, whereby pivotal movement of the support causes planetary movement of said second gear.

7. In combination, a plurality of variable tuning devices, each of said devices having a movable structure for varying its electrical characteristic, as well as a gear mechanically connected to the structure whereby they move in unison, all of said gears intermeshing, whereby the movable structures can be simultaneously operated, and means whereby the gears associated with at least some of the devices can be independently rotated to impart a supplementary movement to the associated movable structure.

8. In combination, a pair of variable tuning devices, each including a gear and a movable structure the position of which determines the tuning, said structure being

connected to the gear, and the gears of both devices being intermeshed, whereby simultaneous variation can be secured, and means for imparting to one of said gears a planetary movement with respect to the other, whereby the device associated with the gear having a planetary movement may be adjusted independently.

9. In combination, a variable tuning device, including a movable structure the position of which determines the tuning, and a gear mechanically connected to said structure, a second tuning device similar to the first mentioned one, a pivotally mounted support for said second device, the axis of the pivot being coincident with that of the gear on the first device, and said second device having a gear meshing with said first-mentioned gear and serving to impart motion 20 to the movable structure of the second device simultaneously with the adjustment of the first device, and means for moving said pivotally mounted support about its axis, whereby a planetary motion is imparted to 25 said second gear.

10. In combination, a tuning device having a movable structure the position of which determines the tuning, and a gear

mechanically connected to said structure, whereby they move in unison, a second tuning device also having a movable structure and a gear mechanically connected thereto, said two gears intermeshing, and a pivotally mounted support for said second tuning device, said support having a pivot with an axis coincident with that of the first gear, whereby pivotal movement of the support causes planetary movement of said second gear.

11. In a device of the class described, a plurality of electrical instruments each having a rotatable shaft for varying the electrical characteristics of the same, each instrument being mounted upon a separate base, means for supporting said instruments in side by side relationship with said shafts spaced and parallel, a gang control for said instruments, and means for moving the base of one of said instruments relative to the bases of the other instruments for effecting 50 individual adjustment of one of said instruments.

In testimony whereof I have hereunto set my hand.

ROGER M. WISE.
